UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,126, dated September 29, 1896.

Application filed August 24, 1896. Serial No. 603,784. Term of patent 31 years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

10 The design consists of an arrangement of ornamental interlacing scrolls with sprays of flowers and leaves connected with said scrolls, as represented in the accompanying drawings.

The border for the said design is also formed of similar interlacing ornamental scrolls with sprays of flowers and leaves, as shown in the drawing.

What I claim is—

1. The design for wall-paper herein shown and described.

2. In the design for wall-paper, the border herein shown and described.

Witness my hand this 10th day of August, 1896.

CHARLES BOOZ.
